CLAIM

The design for a wall-mounted multimedia station, substantially as shown and described.

DESCRIPTION

FIG. 1 is a perspective view of the wall-mounted multimedia station;

FIG. 2 is a front end view thereof;

FIG. 3 is a rear end view thereof;

FIG. 4 is a right side view thereof;

FIG. 5 is a left side view thereof;

FIG. 6 is a top view thereof;

FIG. 7 is a bottom view thereof; and,

FIG. 8 is a second perspective view thereof.

The broken lines shown in FIGS. 1, 2 and 4-8 are for illustrative purposes only and form no part of the claimed design.
